UNITED STATES PATENT OFFICE.

JOHN B. CROFOOT, OF MOUNT PROSPECT, ILLINOIS.

CUSHION CAP FOR TOOLS.

Application filed March 16, 1928. Serial No. 262,254.

My invention relates to cushion caps for tools and more particularly to a cushion cap for stapling machines, having for its object the provision of a device of the kind described of comparatively simple yet efficient construction, and particularly adapted to provide the maximum in the way of a shock absorbing medium for the hand of the operator.

Other objects and advantages of the method and construction herein employed will appear more fully in the accompanying specification and drawings.

In the drawings,

Figure 1 is a side elevation of the embodiment of my invention.

Figure 2 is a plan view thereof.

Figure 3 is a section taken on line 3—3 of Figure 1, looking in the direction of the arrows.

Referring more particularly to the drawings wherein similar characters of reference indicate corresponding parts in the several views, 5 designates the upper body portion of a stapling machine having an operating head 6 resiliently supported by a coil spring 9 seated in a recess 8 formed in the collar 9, the latter having a hole 10 in the base thereof to receive the square plunger shank 11 integral with the head 6 and slidably in a square groove 12 in the end wall 13 of the stapling machine. The above described elements form no part of my invention, being merely detailed for the purpose of more clearly setting forth the functions and mode of operation of my cushion cap when used herewith.

My invention comprises the cap B which is preferably made of comparatively soft elastic rubber formed to provide upper cup shaped recess 13' having a dome shaped cover 14 with a central orifice 15. The bottom of the cap B has a circumferential flange 6 which is flared to receive and clampingly grasp the head 6 of the stapling tool. As best shown in Figure 3, it will be seen the bottom of my cushion cap is configured to provide a shallow recess 16' suitable for the reception of the manipulating head of a stapling machine or other type of percussion tool. On further reference to figure 3, it will be seen that my cap which is formed by the molding process has thickened walls 17, 18 at the point of greatest stress.

The function and mode of operation of

my cushion cap has been in large measure indicated by the foregoing description, but will be made more fully apparent by the following brief explanation. In use, the flange 16 of the bottom socket or recess is flexed over the operating head of the desired tool, which in this case is a stapling machine. To operate the tool, the dome shaped top 14 of the cap B may now be forcibly struck, thereby operating the plunger shank 11, which serves as the hammer, for the purpose of driving the staple through the papers to be attached. The recess or air pocket 13', it will be observed, is closed when the palm or fist lies over the orifice 15, whereby a full pneumatic shock absorbing action is secured. By experience I have found the walls 17 and 18 to be those points most susceptible to breakage, due to the flexure of these parts, and I have accordingly reinforced or thickened these points sufficiently to overcome this defect, while still permitting the desired flexibility to the covering member 14 for the purpose of securing the pneumatic effect alluded to.

I am aware of the use of cushion caps for stapling machines, but I have found the conventional caps now in use either susceptible to early breakage or else insufficiently elastic to permit long continued operation of tools of this type without injury or pain to the operator.

The cushion cap embodying my invention may be used over long periods of time without inconvenience or pain to the operator by reason of the mechanical advantages inherent in its structure, as set forth above.

While I have described and illustrated a preferred form of my invention, it will be understood that minor changes and variations may be made therein, without departing from the spirit or scope of my invention; hence I do not confine myself literally to the details as set forth, but desire to take advantage of such variations and modifications as fairly lie within the province of the appended claims.

What I claim as new and desire to secure by Letters Patent is:

1. A cushion cap for tools comprising a unitary rubber structure formed to provide a bottom socket with an outwardly and inwardly projecting circumferential wall for attachment to a tool head, and an upwardly and inwardly projecting wall forming an air cushion pocket on the top of said cap,

said upwardly and inwardly projecting wall having a central air supply aperture communicating with said pocket, said aperture being of a size adapted to be closed by the 5 hand of an operator when striking said cushion cap immediately over the aperture, whereby the supply of air within the pocket is temporarily confined and compressed to serve as a cushioning means until the hand 10 of the operator is removed, substantially as described.

2. A cushion cap for percussion tools and the like, comprising a unitary rubber structure molded to provide a cushioning pocket 15 having a flared upwardly and inwardly projecting peripheral wall with an air supply-

ing aperture on the top thereof, and an integral socket on the bottom of said cap, said socket being formed by a downwardly and inwardly projecting wall providing a clamping means to secure a tool head within said socket, said air supplying aperture being temporarily closed when the hand of an operator strikes the said upwardly and inwardly projecting peripheral wall, whereby 25 the supply of air within the said cushioning pocket is temporarily confined and compressed until the hand of the said operator is removed.

In testimony whereof I have signed my 30 name to this specification.

JOHN B. CROFOOT.
